UNITED STATES PATENT OFFICE

OSCAR W. ANDERSEN, OF OAK PARK, ILLINOIS, ASSIGNOR TO PETTIBONE MULLIKEN COMPANY, OF CHICAGO, ILLINOIS, A CORPORATION OF DELAWARE

DASHPOT MECHANISM

Application filed May 3, 1929. Serial No. 360,083.

My invention relates more particularly to a dash-pot mechanism of the type employing a liquid, such as oil, the displacement of which in the mechanism serves to effect the desired 5 retarding action; and more especially to dash-pot mechanism forming the retarding means in spring switch constructions.

It is necessary in such dash-pot mechanism that a space be provided into and from which 10 the liquid may flow in the operation of the mechanism, it being desirable that this space be provided in a chamber communicating with the cylinder of the dash-pot mechanism.

My primary object is to provide in dash-pot mechanism of the character above stated 15 means whereby it is impossible, in charging the mechanism with such liquid, to completely fill the chamber referred to and thereby provide a space of sufficient volume to receive 20 the maximum amount of liquid displaced by the mechanism in its operation.

Referring to the accompanying drawings in which I have illustrated my invention as 25 incorporated in dash-pot mechanism forming the retarding means of a spring switch:

Figure 1 is a plan view of such switch mechanism.

Figure 2 is an enlarged section taken at 30 the line 2 on Fig. 1 and viewed in the direction of the arrow.

Figure 3 is an enlarged view taken at the line 3 on Fig. 2 and viewed in the direction of the arrow; and

Figure 4, a fragmentary sectional view, 35 like Fig. 3, of a modification of the construction.

Referring to the particular construction shown, the switch mechanism is of the same construction as that shown in my pending 40 application for United States Letters Patent Serial No. 271,884, filed April 21, 1928, and therefore a general description thereof will suffice.

The switch mechanism shown comprises a 45 cylinder 4 forming one of the elements of dash-pot mechanism, this cylinder being shown as connected at its end portion 5 with a link 6 which in turn is operatively connected with point rails 7 and 8 of a railway switch, 50 these rails being connected together by a

connecting bar 9 to which the link 6 is connected at 10.

Slidable lengthwise in the cylinder 4 is a rod 11 connected at its outer end with the crank arm 12 of a switchstand 13. In the 55 particular construction shown the switchpoints may be set to cooperate with either of the opposing rails of the track, such setting being effected by operating the switchstand.

Slidably mounted on the inner end of the rod 11 between abutments 14 and 15 thereon, are pistons 16 and 17, with a coil spring 18 interposed between, and abutting at its ends 60 against, said pistons.

In one set position of the switchstand one 65 of the pistons engages with one end of the cylinder forming a stop therefor and the other piston is engaged by the adjacent abutment device, with the spring 18 in compressed condition and the switchpoints set against 70 one of the main rails of the track for holding this switch track yieldingly in such position and permitting of the trailing of the wheels therethrough in the movement of a train 75 from the switch track to the main track.

In the other set position of the switchstand the last-referred-to piston abuts against the other end of the cylinder 4 and the other abutment engages the other piston placing 80 the spring 18 under compression in which position of the parts the other switchpoint is yieldingly pressed against the other main rail permitting of trailing through.

The pistons 16 and 15 contain passages 19 and 20, respectively, controlled by check valves 21 and 22, respectively, and the wall of the cylinder 4 adjacent its ends is longitudinally grooved as represented at 23 and 24, 85 respectively.

In use the cylinder 4 is charged with liquid 90 such as oil and the dash-pot mechanism thus provided and comprising the cylinder 4 and the pistons 16 and 17 and the rod 11, serves to retard the return of the switchpoints to their normal set positions relative to the rails which they oppose, when moved from either of their two set positions. Assuming the setting of the mechanism as shown in Figs. 1 and 2, the trailing of a train from the switch 100

track onto the main track forces the switchpoints in a direction away from the switchstand, with no, or practically no, resistance by the oil in the cylinder 4 as the oil displaced in the cylinder by this movement flows through the passage 19, the check valve 21 automatically opening. The return of the switchpoints to the set position shown in Fig. 1 is, however, retarded because in the movement of the cylinder 4 toward the switchstand the oil between the piston 16 and the adjacent end of the cylinder must be displaced around the piston through a restricted passage.

15 When the switchpoints are set reversely to that shown in Fig. 1 the movement of the cylinder 4 by the trailing of a train on the main track through the switch in the movement of the train to the left in Fig. 1, is toward the switchstand, the oil freely passing through the passage 20 in the piston 17, but upon the return movement of the switchpoints to the set position last referred to, under the action of the spring 18, is required to pass around the piston 17 through the restricted passage at this end of the cylinder thereby effecting the desired retarding action.

30 The dash-pot mechanism shown comprises, in addition to the cylinder 4 for the oil, a chamber 25 in communication at 26 with the interior of the cylinder 4 the purpose of which is to ensure maintenance of the cylinder 4 completely filled with oil at all times, 35 the oil, in accordance with my invention, and charged into the apparatus, only partially filling the chamber 25 to provide a space at the upper portion of this chamber of such size that the maximum amount of oil displaced 40 from the cylinder 4 into the chamber 25, in the operation of the dash-pot mechanism, may be received into this chamber. In accordance with the disclosure in Figs. 1, 2 and 3, the chamber 25 is provided with a vertical 45 filler opening 27 shown as closed by a removable plug 28 through which the oil to be introduced into the cylinder 4 is poured. Communication between the chamber 25 and the interior of the cylinder 4 is preferably afforded through the plug 28 which contains the passage 26 opening into a cross passage 29 in the plug, the inner end of the plug preferably extending into an opening 30 in the bottom wall of the chamber 25 and in line 50 with the opening 27.

To ensure against the complete filling of the chamber 25 with oil, for the purpose above stated, the wall represented at 31 and surrounding the opening 27 is formed to depend below the underside of the chamber 25, as shown, this wall being preferably formed by casting a depending rib as shown more particularly in Fig. 3 transversely across the upper portion of the chamber 25 and through which the opening 27 extends. By providing

the depending wall just referred to about the opening 27, the oil charged into the apparatus in the filling operation will not rise in the chamber 25 above the level of the lower surface of the wall 31 thereby ensuring a space, 70 filled with air, between the upper level of the oil and the top of the chamber 25, this space being of sufficient volume to receive the maximum amount of oil displaced into the chamber 25 in the operation of the mechanism. 75

The modified construction shown in Fig. 4 is the same as that of the preceding figures except that, instead of providing the plug 28 as shown therein, a short plug represented at 32 is provided and interposed between this plug and the top wall of the cylinder 4 is a removable and replaceable tubular member 33 which seats at its lower end in an annular recess 34 in the wall of the opening 30 and extends at its upper end into the opening 27. The side-wall of the member 33 is perforated as represented and contains a cup-shaped screen 35 reaching short of the bottom surface 80 of the chamber 25.

The screen 35 serves to prevent lint, or other particles, in the oil supplied to the mechanism from entering the cylinder 4, while the perforations in the member 33 afford passages through which the oil may sufficiently freely flow from cylinder 4 to chamber 25, and vice versa, in the operation of the mechanism. 85

90 While I have illustrated and described certain particular constructions embodying my invention I do not wish to be understood as intending to limit it thereto as the same may be variously modified and altered without departing from the spirit of my invention. 95

100 What I regard as new, and desire to secure by Letters Patent, is:

1. A cylinder device for the purpose set forth, comprising a chamber containing an opening through which it communicates with the interior of the cylinder, said chamber having a filler-opening in its top, a tubular member interposed in the space between said openings and having an opening in its side in communication with said chamber and cylinder, and a screen associated with said member and extending above said first-named opening. 110

115 2. A cylinder device for the purpose set forth, comprising a chamber containing an opening through which it communicates with the interior of the cylinder, said chamber having a filler-opening in its top, a tubular member interposed in the space between said openings and having an opening in its side in communication with said chamber and cylinder, and a screen in said tubular member and extending above said first-named opening. 120

125 3. A cylinder device for the purpose set forth, comprising a chamber containing an

opening through which it communicates with the interior of the cylinder, said chamber having a filler-opening in its top, a tubular member interposed in the space between said openings and a screen associated with said member and extending at its lower portion between said openings, the sides of said member being apertured between said openings both above and below the lower portion of

10 said screen.

4. A cylinder device for the purpose set forth, comprising a chamber containing an opening through which it communicates with the interior of the cylinder, said chamber having a filler-opening in its top, a tubular member interposed in the space between the said openings and having an opening in its side in communication with said chamber and cylinder, and a plug in said filler opening.

15 5. A cylinder device for the purpose set forth, comprising a chamber containing an opening through which it communicates with the interior of the cylinder, said chamber having a filler-opening in its top, a tubular member interposed in the space between said openings and having an opening in its side in communication with said chamber and cylinder, a screen associated with said member and extending above said first-named opening, and a plug in said filler opening.

20 6. A cylinder device for the purpose set forth, comprising a chamber containing an opening through which it communicates with the interior of the cylinder, said chamber having a filler-opening in its top, a tubular member interposed in the space between said openings and having an opening in its side in communication with said chamber and cylinder, and a cup-shaped screen located in said member and extending above said first-named opening.

25 7. A cylinder device for the purpose set forth, comprising a chamber containing an opening through which it communicates with the interior of the cylinder, said chamber having a filler-opening in its top, a tubular member interposed in the space between said openings and having an opening in its side in communication with said chamber and cylinder, a cup-shaped screen located in said member and extending above said first-named opening, and a plug in said filler opening.

30 8. A cylinder device for the purpose set forth, comprising a chamber containing an opening through which it communicates with the interior of the cylinder, said chamber having a filler-opening in its top, a tubular member interposed in the space between said openings and a cup-shaped screen associated with said member and extending at its lower portion between said openings, the sides of said member being apertured between said openings both above and below the lower portion of said screen.
